UNITED STATES PATENT OFFICE.

HENRY B. MYERS, OF SCHOOLCRAFT, MICHIGAN.

IMPROVEMENT IN WIND-WHEELS.

Specification forming part of Letters Patent No. 222,072, dated November 25, 1879; application filed May 10, 1879.

To all whom it may concern:

Be it known that I, HENRY B. MYERS, of Schoolcraft, in the county of Kalamazoo and State of Michigan, have invented certain new and useful Improvements in Wind-Wheels; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a face of my wind-wheel. Fig. 2 is a side-elevation view; and Fig. 3 is a plan view.

Identical parts in the drawings are designated and referred to by the same letters.

My invention relates to windmills; and it consists in two wind-wheels constructed to be driven in opposite directions by the wind, both driving one power-shaft, one wheel being the same diameter as the eye of the larger wheel, constructed for the purposes herein more fully set forth.

A represents the windmill-frame. B is a hollow stem passing through the top of the frame and resting in a proper socket at b. This stem or standard turns freely in its position. The upper portion of this standard is bifurcated, and provides a bearing of sufficient length to properly hold the shafts of the two wind-wheels C and D.

C is the smaller wheel of the two, and is constructed with rigid feathers. Upon the inner end of the shaft of this wheel there is a bevel-pinion, C', which meshes with the bevel-pinion C². This pinion C² is rigidly attached to the power-shaft E, which is located in the hollow of the standard B.

D is the larger wind-wheel. The distance between the inner ends of opposite feathers or the eye of this wheel is about equal to the extreme outside diameter of smaller wheel, C. Upon the inner end of the shaft of this wheel D there is also a bevel-pinion, D', which is larger than the pinion C'. This pinion meshes with a bevel-pinion, D², which is also rigidly attached to the shaft E. This pinion D² is larger than the corresponding pinion C², and the parts described are so constructed and arranged that they revolve the same number of times in a given number of revolutions of the

shaft E, and, being located upon opposite sides of the shaft E, their reverse motions drive the shaft E in the same direction.

F is a frame for supporting the vanes. This frame is supported by the curved braces f, f, which are securely attached to the head of the standard B.

G, H, and K are the vanes for controlling the position of the wind-wheels in relation to the wind, and they are firmly supported in their position by their stems g, h, and k, resting in their respective boxes g', h', and k'.

The vanes G and H are for holding the wind-wheels facing the current of the wind for operation, and to retain them in their position. Their stems are journaled in their boxes, and provided with a weighted arm, g² and h². These stems g and h are also provided with arms g³ and h³.

The stem k is provided with an arm, k², which is connected with the angled lever L by the connecting-rod l. This lever L is pivoted to the frame F near its center, and its lower arm provided with a weight, l', and its upper one with a vane, l². This stem k is also provided with the arms k⁴ and k², which engage the arms g³ and h³.

The operation of my invention is as follows: When the mill is set for action, the vanes G and H are vertical and the vane K is horizontal. In case the wind is too strong in its current the vane l is blown back, the weight l' being properly adjusted. The motion of the lever L revolves the stem k and turns the vane K up to wind, and at the same time the arms k² and k⁴ engage the arms g³ and h³, and turn the vanes G and H down in a horizontal position, when the vane K, controlling the wind-wheels, will cause them to be turned from the wind.

The vane l² is set a little quartering, so as to be acted upon by strong currents; but as they subside, or the mill is partially turned from them, the vane l² is returned, wholly or in part, by the weight l'.

The weighted arms g² and h² return the vanes G and H to a vertical position, wholly or in part, as the current of the wind moderates or increases in force.

By this means I am enabled to automatically protect my windmill from injury, and at the

same time preserve nearly a uniform motion to the mill.

In case it is desired to stop the mill, it is done by drawing down upon a rope which is attached by a half or quarter turn to the shaft k , and passes down the inside of the hollow shaft or stem B.

Instead of the arms g^3 and h^3 engaging the arms k' and k^2 , I may use bevel-gear, if I find it preferable, situated upon their respective shafts or stems, and meshing, to secure more certain and positive action.

I do not wish to confine myself to wind-wheels of the exact proportions herein described, as it is my purpose to have one wheel about the size of the eye of the other; nor do I wish to confine myself to the relative position of the wind-wheels, as it may be found expedient to place the larger wheel to the windward of the smaller one. I may also dispense with one of the bevel-gears on the power-shaft and connect both wheels with one pinion on the power-shaft.

Having thus described my invention, what I claim as new, and desire to secure by Letters Patent, is—

1. In a windmill, the combination of the wind-wheels C and D with the power-shaft E, the wind-wheel D being constructed with

an eye in diameter about equal to the outside diameter of wheel C, as and for the purposes set forth.

2. In a windmill the vanes G and H, provided with the weighted arms g^2 and h^2 and arms g^3 and h^3 , in combination with vane K, provided with the stem k , arms k^2 and k^3 and k^4 , and the lever L, provided with the weight l' and vane l^2 , as and for the purposes substantially as set forth.

3. In a windmill, the lever L, provided with the vane l^2 and the adjustable weight l' , in combination with the stem k and vanes G and H, as and for the purposes substantially as set forth.

4. In a windmill, the wind-wheels C and D, in combination with the power-shaft E, the hollow stem B, the frame F, and vanes G, H, and K, and the lever L, provided with the adjustable weight l' and vane l^2 , set quartering, as and for the purposes substantially as set forth.

In testimony that I claim the above I have hereunto subscribed my name in the presence of two witnesses.

HENRY B. MYERS.
